UNITED STATES PATENT OFFICE.

JOHN W. WILLIAMSON, OF NEW YORK, N. Y.

SAFETY HAIR-CUTTER.

1,074,678.

Specification of Letters Patent.

Patented Oct. 7, 1913.

Application filed November 20, 1912. Serial No. 732,516.

To all whom it may concern:

Be it known that I, JOHN W. WILLIAMSON, a citizen of the United States, and a resident of New York, borough of Brooklyn, county of Kings, and State of New York, have invented a certain new and useful Improvement in Safety Hair-Cutters, of which the following is a full, clear, and exact specification.

10 This invention relates more particularly to a class of devices adapted to enable a person to cut his own hair.

My invention has for its object primarily to provide a safety hair cutter, or device designed to be utilized by persons for cutting their own hair and especially those having stiff kinky hair, and which is of a form that will allow the device to be also employed as a razor whereby the person may shave himself without any danger of cutting the skin. This is accomplished mainly by providing a comb which serves as a guard, and employing in conjunction therewith a razor blade adapted to be adjusted in a manner so as to permit the device to be conveniently manipulated for cutting the hair in a suitable style, or if desired the razor blade may be swung to a position relatively to the comb and used for shaving.

20 Other objects of the invention are to provide means adapted to enable the comb and blade to be accurately guided while the hair is being trimmed; to provide a form of holder which will permit a razor blade 25 when dulled to be replaced by another blade; and to provide a safety hair cutter wherein the various parts thereof may be detachably connected together.

With these and other objects in view, the 30 invention will be hereinafter more particularly described with reference to the accompanying drawing, which forms a part of this specification, and will then be pointed out in the claims at the end of the description.

45 In the drawing, Figure 1 is a side elevation of one form of safety hair cutter embodying my invention. Fig. 2 is a side elevation of a form of holder and blade used 50 in the device. Fig. 3 is a side elevation of a form of guard employed in the device. Fig. 55 4 is a view, partly in section, of one end of the comb used in the device. Fig. 5 is a view through the comb adjacent to one end thereof showing part of the guide used in conjunction with the device, and which sec-

tionally illustrates the cutting blade and holder thereof applied to the comb. Fig. 6 is a section through the holder, the cutting blade, and the guard shown in Fig. 3. Fig. 60 7 is a side elevation of a small guard employed upon one end of the comb. Fig. 8 is a side elevation, partly fragmentary, of the comb and blade when used for shaving, and Fig. 9 is a perspective view of the guide 65 used in conjunction with the device.

The safety hair cutter, or device has a comb 10 which may be of any suitable shape, or size, and said comb may be provided with either coarse, or fine teeth 11 as preferred. 70 Upon one surface of the comb 10, and at each end thereof are a number of spaced compressible teats, or buttons, as 12 and 13, each of which may be of the well known make having a hollow body of spring metal 75 with a number of spaced slots therein so as to yieldingly permit a blade holder, as 14, to be removably fastened to the comb 10.

The blade holder 14 has an elongated body 15 which is preferably formed by 80 bending a sheet of spring metal, or other like material lengthwise into approximately the shape of an inverted U, as viewed in cross-section, whereby two spaced arms are provided, and one of the arms of said body 85 is somewhat longer than the other arm. The free edges of the arms of the body 15 are curved inwardly toward each other, as at 16 and 17, and upon the ends of the short arm are extensions 18 and 19 through each 90 of which is an opening 20 and 21. The openings 20 and 21 are of diameters to permit each to receive therethrough one of the buttons 12 and 13 by the use of slight pressure so as to fasten the holder to the comb, 95 and to permit the holder to be likewise disconnected therefrom. Between the arms of the holder 14 is inserted a blade 22 adapted to be employed for cutting the hair and for shaving, as will be hereinafter more fully 100 described.

The blade 22 is preferably of the same length as the body 15 of the holder 14, and may be of any suitable width. Both of the longitudinal edges of the blade 22 is 105 sharpened to a knife edge, and substantially midway of said blade is a longitudinally disposed ridge 23 which is formed by depressing one surface of the blade whereby a groove, as 24, is provided. In order to 110 hold the blade 22 against accidental displacement when applied to the holder 14 the blade

is inserted therein so that the curved edge 17 of the short arm of the body 15 thereof will be disposed in the groove 24 and the curved edge 16 of the other arm of the body 5 will overlap and engage the ridge 23, as shown in Fig. 6 of the drawing.

When the device is used for cutting the hair of the head of a person, the holder 14 with the blade 22 mounted therein is applied 10 upon the comb by positioning the holder so that one of the buttons 12 and 12 at each end of the comb will be guided through the openings 20 and 21 of the extensions 18 and 19 of said holder, as indicated in Fig. 1. By 15 guiding the comb 10 and the blade 22 over the head of a person somewhat after the fashion of using an ordinary comb the hair will be trimmed the required length, and the comb 10 will serve as a guard to prevent the 20 blade from cutting the scalp.

In order to permit parts of the hair to be trimmed especially in proximity to the ears of a person, upon the surface of the comb 10 to which the blade holder 14 is applied and 25 at one end thereof is a small guard, as 25, having a plurality of teeth 26 in one of its edges, and upon this guard is a small second blade 27 of the same width as the guard. Both the guard 25 and blade 27 are rigidly 30 secured to the comb by a screw, or the like which is passed through registered openings in the blade, the guard, and the comb.

For the purpose of permitting the comb 10 and the blade 22 to be accurately directed 35 when in use, upon the surface of each end of the comb which is opposite to the holder 14 and blade 22 are two spaced compressible buttons 28 and 29 which are of a similar formation to the buttons 12 and 13, and said 40 buttons 28 and 29 serve to allow a guide, as 30 Fig. 9, to be removably applied to the comb 10. The guide 30 has two spaced walls 31 and 32 which are spaced apart a distance approximately the length of the comb 10. 45 The walls 31 and 32 are substantially triangular in shape, and said walls are connected by a transverse strip 33. Projecting in opposite directions from the vertical straight edges of the walls 31 and 32 are 50 flanges 34 and 35 through each of which may be one, or more holes 36 and 36^a. The holes 36 and 36^a are of diameters whereby the buttons 28 and 29 may be passed therethrough by the exertion of slight pressure 55 upon said flanges. When the comb, the holder with its blade, and the guide 30 thus attached together are guided over the hair the transverse strip 33 will contact with the head, and the comb and blade will be disposed upon a suitable incline for trimming 60 the hair conveniently and evenly.

When the device is employed for shaving the holder 14 and blade 22 are removed from the comb 10, and one end of the holder is 65 pivotally fastened upon one of the buttons

12 or 13 at one end of the comb, as shown in Fig. 8. The holder 14 and blade 22 may then be swung to a suitable angle relatively to the comb 10 which will serve as a handle instead of as a guard. At spaced intervals 70 upon one surface of the holder 14 are two teats, or buttons 37 and 38 which are also formed similarly to the buttons 12 and 13 so as to be compressible. Adapted to be removably applied upon the holder 14 is an elongated guard 39, Figs. 3, 6, 8, having two spaced holes 40 and 41 of diameters whereby the buttons 37 and 38 may be disposed therethrough by the use of slight pressure. The guard 39 is preferably of the usual 75 form having spaced teeth 42 upon one of its edges, and the free ends of said teeth are slightly curved, at 42, so as to be disposed whereby the teeth will contact with the skin in advance of the contact of the blade therewith when said guard 39 is applied to the holder and to the blade for shaving a person. 80

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof. 95

Having thus described my invention, I claim as new and desire to secure by Letters Patent:—

1. In a safety hair cutter, a comb, a plurality of spaced compressible buttons provided upon one surface at each end of the comb, an elongated holder of substantially the shape of an inverted U in cross section, the free lengthwise edges of the arms of the holder being curved and disposed toward each other, two extensions, one provided upon each end of the holder and each of said extensions having a hole therethrough for reception of one of the compressible buttons at each end of the comb whereby the holder may be removably held thereto so that the comb will serve as a guard when the cutter is in use, and an elongated blade having a groove lengthwise thereof, said blade being removably inserted between the arms of the holder whereby the curved edge of one of the arms will be disposed in the groove of said blade. 100

2. In a safety hair cutter, a comb, an elongated holder of substantially the shape of an inverted U in cross section, the free lengthwise edges of the arms of the holder being curved and disposed toward each other, two extensions, one provided upon each end of the holder and each of said extensions having a hole therethrough, means provided at each end of the comb and adapted to engage with the openings of the exten- 105 110 115 120 125 130

sions of the holder whereby the holder may be removably held thereto so that the comb will serve as a guard when the cutter is in use, an elongated blade removably inserted 5 between the arms of the holder, and a guide removably held upon the opposite surface of the comb, said guide being adapted to contact with the head for disposing the comb and the blade at a suitable angle for 10 cutting the hair.

3. In a safety hair cutter, a comb, a plurality of spaced compressible buttons provided upon one surface at each end of the comb, an elongated holder of substantially 15 the shape of an inverted U in cross section, the free lengthwise edges of the arms of the holder being curved and disposed toward each other, two extensions, one provided upon each end of the holder and each of 20 said extensions having a hole therethrough for reception of one of the compressible buttons at each end of the comb whereby the holder may be removably held thereto so that the comb will serve as a guard when 25 the cutter is in use, an elongated blade having a groove lengthwise thereof, said blade being removably inserted between the arms of the holder whereby the curved edge of one of the arms will be disposed in the 30 groove of said blade, a guide, and means serving to detachably hold the guide to the opposite surface of the comb, said guide being adapted to contact with the head for disposing the comb and the blade at a suitable angle for cutting the hair.

4. In a safety hair cutter, a comb, an elongated holder of substantially the shape of an inverted U in cross section, the free lengthwise edges of the arms of the holder 40 being curved and disposed toward each

other, means adapted to removably hold the holder upon one surface of the comb so that the comb will serve as a guard when the cutter is in use, an elongated blade having a groove lengthwise thereof, said blade being 15 removably inserted between the arms of the holder whereby the curved edge of one of the arms will be disposed in the groove of said blade, and a guide removably held upon the opposite surface of the comb, said 50 guide being adapted to contact with the head for disposing the comb and the blade at a suitable angle for cutting the hair.

5. In a safety hair cutter, a comb, a plurality of spaced compressible buttons provided upon one surface at each end of the comb, an elongated holder of substantially 55 the shape of an inverted U in cross section, two extensions, one provided upon each end of the holder and each of said extensions 60 having a hole therethrough for reception of one of the compressible buttons at each end of the comb whereby the holder may be held thereto, an elongated blade removably inserted between the arms of the holder whereby the curved edge of one of the arms will be disposed in the groove of said blade, a plurality of spaced alined compressible buttons provided upon the opposite surface of the comb, and a guide having a plurality of 65 spaced holes through each of which one of the latter said buttons of said holder is passed so that the guide may be removably held thereto.

This specification signed and witnessed 75 this nineteenth day of November, A. D. 1912.
